UNITED STATES PATENT OFFICE.

HUGO LENTZ, OF BERLIN, GERMANY, ASSIGNOR OF ONE-HALF TO
CHARLES BELLENS, OF NEUILLY-SUR-SEINE, FRANCE.

VALVE-GEAR FOR ENGINES.

No. 822,136.

Specification of Letters Patent.

Patented May 29, 1906.

Application filed October 10, 1905. Serial No. 282,177.

To all whom it may concern:

Be it known that I, HUGO LENTZ, a subject of the Emperor of Germany, residing at Berlin, in the Kingdom of Prussia and German Empire, have invented new and useful Improvements in Valve-Gears for Engines, of which the following is a specification.

My invention relates to that class of steam-locomotive cylinders the valves of which are actuated by a rod presenting valve-lifting surfaces, reciprocating in a longitudinal tubular member, while the valve-stems are guided in four tubular members located at right angles to the longitudinal one.

The invention consists in improvements in such mechanism with a view to insuring better protection of the various parts of the gear from atmospheric influences, dust, &c., and to effecting thorough lubrication of all movable parts from a common lubricating device. For this purpose the tubular members guiding the valve-stems are open at the top and inclosed in a box-shaped chamber closed above by a hollow cover, the space in which serves as common oil-reservoir.

My invention is illustrated in the accompanying drawings, in which—

Figure 1 is a longitudinal section on the line A B of Fig. 2, and Fig. 2 a cross-section on the line C D of Fig. 1.

The tubular guiding parts $m m' m^2 m^3$, in which the roller-holders of the valve-stems $a b c d$ are guided, are open at the top and inclosed in a chest or casing e . The cover f of this casing thoroughly closes the latter at the top and presents recesses $g g' g^2 g^3$ on the inner surface, into which recesses there fit the springs $h h' h^2 h^3$, which effect closing of the valves, the other ends of which springs enter shallow recesses in the heads of the roller-holders. The cover f is hollow, and the chamber so presented serves as oil-reservoir and is provided with oil-ducts $i i' i^2 i^3$ above the guides m to m^3 . The lubricant is fed through the ducts i to i^3 into the chest e and first to the roller-holders and to the valve-stems. At the same time the lubricant also flows to the lifter-rod o , working in the guide k .

The lubricant-reservoir in the cover is provided above the oil-distributing ducts i to i^3 with apertures through which each distributing-duct is accessible. These apertures may be closed—for instance, by simple screw-plugs $n n' n^2 n^3$. The apertures may also

serve for filling the lubricant into the reservoir; but the lubricant can naturally also be fed continuously to the reservoir in suitable manner, if desired.

For the purpose of insuring common lubrication and uniform distribution of the lubricant to all moving parts, including such as are below the lifter-rod o , passages $p p'$ are furnished below the latter to enable flow of oil between the guides $m m'$ and $m^2 m^3$ and the stems $a b$ and $c d$, respectivley, and these passages $p p'$ communicate, by means of holes $q q'$, with the interior of the guide k , so that they receive lubricant from this guide k and the casing e . The passages $p p'$, closed at the outer end by plugs $r r'$, may also be supplied with oil—for instance, at $s s'$ —by a separate oil-feed device.

The provision of the casing or box e affords the most effectual protection for the valve-gear parts from external influences and the entrance of dust or the like, and even should the plugs n to n^3 be removed nothing can obtain access to the gear parts which would exercise an injurious effect upon them. The employment of a common oil-reservoir with provision for distribution of the lubricant to all parts of the gear affords full guaranty for thorough and uniform lubrication. The consumption of oil also is essentially diminished, and the use of the reservoir e offers the additional advantage of enabling the collected oil and the water of condensation to be run off.

Having thus described my invention, what I claim as new, and desire to secure by Letters Patent, is—

1. A valve-gear for engines having lift-valves actuated by a lifter-rod, a tubular guide presenting a longitudinal guideway for the rod and guideways for the valve-stems located at right angles to the longitudinal guideway and open at the top, and a single casing inclosing all of the valve-stem guideways and provided with a cover, substantially as described.

2. A valve-gear for engines having lift-valves actuated by a lifter-rod, a tubular guide presenting a longitudinal guideway for the rod and guideways for the valve-stems located at right angles to the longitudinal guideway and open at the top, and a casing inclosing the valve-stem guideways and closed by a hollow cover which serves as lubricant-container, substantially as described.

3. A valve-gear for engines having lift-valves actuated by a lifter-rod, a tubular guide presenting a longitudinal guideway for the rod and guideways for the valve-stems 5 located at right angles to the longitudinal guideway and open at the top, and presenting oil-channels located between the valve-stem guideways and below the lifter-rod, and a covered casing inclosing the valve-stem

guideways and communicating with the said 10 channels, substantially as described.

In testimony whereof I have hereunto set my hand in the presence of two subscribing witnesses.

HUGO LENTZ.
